UNITED STATES PATENT OFFICE

ARTHUR M. SMITH, OF OAKLAND, CALIFORNIA, ASSIGNOR TO THE ROME COMPANY, INC., OF ROME, NEW YORK, A CORPORATION OF NEW YORK

DOOR MOUNTING

Application filed September 18, 1928. Serial No. 306,729.

This invention relates to a door mounting.

It is the object of my invention to provide a door mounting which will permit the door to close its own opening at all times, regardless of obstructions in the doorway, on one side or the other. Such problems arise in connection with concealable furniture, wherein an article such as a bed is pivotally mounted adjacent one edge of a door opening, so as to permit an article of furniture wider than the door opening to be moved therethrough from a closet or receptacle out into a room, where it is to be used. As a result of this, the article of furniture extends part way across the door opening both when it is stored and when it is positioned outside for use. This interferes with the closing of the door when the article is exposed for use; and in the present invention I provide a mounting for the door whereby the door may be moved into closed position at all times.

When the article is stored, the door will have the appearance of an ordinary, hinged door, and may be swung open so as to permit the article of furniture to be removed from the receptacle or closet, after which the door may be moved through a path which will cause it to reverse its position and close the opening while the article of furniture extends part way across the opening.

A further object and advantage of the present mounting is that the door may be swung inwardly to open position when in its reversed position, so that access may be had to the closet when the article of furniture is exposed outside thereof.

One form which my invention may assume is exemplified in the following description and illustrated in the accompanying drawing, in which:

Fig. 1 shows a perspective view of a closet or receptacle containing an article of furniture provided with a door equipped with the present invention;

Fig. 2 shows a plan view in section of the same, with the article of furniture in concealed position and the door closed;

Fig. 3 shows a similar view, with the door open;

Fig. 4 shows a similar view, with the article

of furniture exposed and the door in reversed position, closing the opening.

Fig. 5 shows a detail perspective view of the track and shoe.

In the form herein illustrated, I show a receptacle or closet 10, to receive an article of furniture, such as a bed 11. This closet is provided with an opening which is less in width than the bed, through which the bed is turned about vertical pivots 12, arranged adjacent one of the edges of the door opening.

The opening is closed by a door 13, which is so mounted as to completely close the opening both when the bed is stored and when it is exposed on the opposite side for use, it being noted that in either position of the bed it extends part way across the opening, so as to form an obstruction to the ordinary, hinged door. This door is connected by hinges 14 to a yoke member 15 which extends vertically adjacent the edge of the opening opposite the pivots 12. This yoke member 15 is provided with horizontal arms 16 which are pivotally mounted in the top and bottom frame members of the opening at a point exactly half way between the edges of the opening.

Connected to the top yoke arm is a guide link 17, which in turn connects with a shoe 18, slideable in a track 19, the track being secured to the top frame member of the door opening. This shoe carries a pin or projection 20 which fits in a groove 21 in the top of the door, said groove extending from one edge thereon to a point short of the opposite edge, where it is provided with an outlet 22.

In the operation of the door, and assuming that the article of furniture is concealed within the closet and the door is closed, as shown in Fig. 2, said door may be opened as in the case of an ordinary, hinged door, by swinging it outwardly to a right-angle position, as shown in Fig. 3. The article of furniture may now be swung outwardly into the space on the opposite side of the closet, after which the door can be closed by thrusting inwardly upon it, which will cause its hinged edge to swing around through an arc of 180° upon the yoke member 15 to the position shown in Fig. 4. During this re-

versal of the position of the door it will be guided by the pin 20, sliding through the groove 21, and the guide link 17, which serves to shift the shoe 18 from a position at one end of the track to a position at the opposite end of the track, the link in the meantime passing from a folded position with respect to the yoke arms, into a straightened position.

10 In reversing the position of the door, it passes from the front side of the yoke member to the rear side thereof, and lies behind the pivots 12. The outlet 22 is provided, in order that the door in reversed position may lie in the plane of the door opening. This outlet is formed in line with the position of the pin 20 when the door is reversed; therefore the pin automatically moves out of the groove and allows the door to assume a position in alignment with the plane of the opening. Furthermore, on account of the withdrawal of the pin from the slot, the door when in reversed position will be free to swing inwardly, as shown in dotted lines in Fig. 4, and thus permit access to the closet when the article of furniture is on the outside. In restoring the door to normal position, the operation of the parts is such that the pin will re-enter the groove without any attention on the part of the operator.

25 The present door mounting obviously may be employed in many different situations, not necessary to be illustrated herein; and it is also apparent that various changes in the construction and operation of the several parts herein shown and described may be employed without departing from the spirit of my invention as disclosed in the appended claims.

40 The present mechanism may also be used in conjunction with mechanism which would connect a door and bed in such a way that when the door is opened and reversed the bed will be withdrawn from the closet and disposed on the opposite side of the opening in position for use.

45 Having thus described my invention, what I claim as new and desire to secure by Letters Patent is:

50 1. A door having hinges at one edge, a swinging support for the hinges, reversible within the door opening, and connecting means between the swinging support and the door, to guide the latter, whereby the door will be reversed coincident with reversal of the support.

55 2. A door having hinges at one edge, a swinging support for the hinges, reversible within the door opening, and connecting means between the swinging support and the door, to guide the latter, whereby the door will be reversed coincident with reversal of the support, said guide means permitting the door to swing about its hinges in one direction when in normal position and in

the opposite direction when in reversed position.

60 3. The combination of a door and its opening, a portion of which opening is always obstructed, hinges at one edge of the door, a swinging support for the hinges, reversible within the door opening, a track on one of the horizontal borders of the door opening, a shoe slidable in the track and a link connecting the shoe with the swinging support, and a projection on said shoe, slidable in a groove in the adjacent edge of the door.

65 4. The combination of a door and its opening, a portion of which opening is always obstructed, hinges at one edge of the door, a swinging support for the hinges, reversible within the door opening, a track on one of the horizontal borders of the door opening, a shoe slidable in the track and a link connecting the shoe with the swinging support, a projection on said shoe, slidable in a groove in the adjacent edge of the door, and an outlet for the groove, whereby the door may be swung on its hinges when in reversed position.

70 5. In combination with a closet having an opening, an article of furniture pivotally mounted adjacent one edge of the opening so as to be moved through the opening, said article being wider than the opening and therefore forming a partial obstruction to the opening on either side, a door for closing the opening, hinges for one edge of the door, and a swinging support for the hinges, reversible within the opening, whereby the door may be opened to permit the article to be moved through the opening and reversed so as to close the opening when the article is disposed on the opposite side of the opening.

75 6. In combination with a closet having an opening, an article of furniture pivotally mounted adjacent one edge of the opening so as to be moved through the opening, said article being wider than the opening, and therefore forming a partial obstruction to the opening on either side, a door for closing the opening, hinges for one edge of the door, a swinging support for the hinges, reversible within the opening, whereby the door may be opened to permit the article to be moved through the opening and reversed so as to close the opening when the article is disposed on the opposite side of the opening, and guide means whereby the path of movement of the door during reversal is controlled.

80 7. In combination with a closet having an opening, an article of furniture pivotally mounted adjacent one edge of the opening so as to be moved through the opening, said article being wider than the opening and therefore forming a partial obstruction to the opening on either side, a door for closing the opening, hinges for one edge of the door, a swinging support for the hinges, re-
